UNITED STATES PATENT OFFICE.

HELEN S. ROWLAND, OF ST. PETERSBURG, FLORIDA.

HAIRPIN BARRETTE.

Application filed June 26, 1928. Serial No. 288,317.

This invention relates to the class of toilet articles and pertains particularly to a barrette.

The primary object of this invention is to provide a barrette having the appearance of a hair pin and formed to so fold and clasp the hair that it cannot easily become loosened and lost and when in use it will have the appearance of a hair pin in the hair.

10 The present invention is so designed that the usual metal hair pins or metal hair pin wire may be employed for making the same, the ends of the pins being secured together to form the same in the shape of elongated loops, 15 one end of one loop being rolled over one end of an adjacent loop to hingedly connect the two together. One of the loops at its other end is turned upwardly and the adjacent end of the other loop is designed to snap therebe- 20 neath to frictionally hold the loops together.

A particular feature of the barrette embodying the present invention is the clasp means employed for maintaining the two sections of the barrette together, this clasp being such that the sections are securely connected when in use and at the same time a disconnection may be made quickly and easily.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

40 In the drawings:—

Figure 1 is a plan view of the barrette embodying this invention; the same being in opened condition;

Figure 2 is a view in side elevation of the 45 opened barrette;

Figure 3 is a longitudinal sectional view of the barrette in closed condition.

Referring to the drawing in detail it will be seen that the present device comprises two 50 members indicated by the numerals 1 and 2, each of these members being in the form of an elongated loop. The member 1 which, like the member 2, is formed of a wire hair pin having the ends thereof secured together, has 55 a cross bar 3 at one end while at the opposite

end a similar but shorter cross member 4 is formed, this opposite end being turned slightly to arrange the bar 4 in a different plane but parallel to the plane in which the side members 5 of the loop are located.

As will be readily seen, the side members or legs of the loop 1 converge from the ends of the cross bar 3 to the point where they turn outwardly to connect to the cross or latch bar 4.

60 The member 2, like the member 1, also has the legs 6 thereof connected at one end by the cross bar 7, the legs 6 extending therefrom in convergent relation to the yoke or rounded tip 8 at the opposite end.

65 The members 1 and 2 are coupled together by arranging the bar 7 of the member 2 over the legs 5 of the member 1 adjacent the bar 3 thereof and then rolling or looping the ends of the legs 5 adjacent the bar 3 to form 70 the hinge eyes 9 through which the bar 7 loosely extends. These hinge eyes are each set in a plane lying at an acute angle with respect to the longitudinal center of the member 1 and diverging in the direction of the 75 remote end thereof. It will thus be seen that part of each eye lies in the path of movement of one side of the member 2 so that when the members are brought together the sides or legs of the member 2 will be sprung out by 80 and will engage under the eyes and be held thereby.

70 The relative lengths of the members 1 and 2 are such that when the same are connected together in the manner described and one of the members brought in superposed relation to the other the rounded end 8 of the member 2 will snap under the latch bar 4 at the outer end of the member 1 and thus hold the two 85 loops securely in juxtaposition.

90 In order to increase the gripping action of the loop legs 5 and 6, pins having corrugated legs may be employed or, of course, if the loops are made of ordinary wire and bent to the form of the hair pin, the same may be 95 corrugated in the manner shown.

From the foregoing description, it will be readily seen that a barrette of the type described will have a relatively wide hair engaging area and will be easy to apply and remove from position.

100 Having described my invention what I claim is:—

110 1. A barrette of the character described, comprising a pair of elongated loop members

- each being of greater width at one end than at the other and each having a bar member formed across its wide end, hinge eyes formed of the side bars of one loop adjacent the wide end of the same and having the cross bar of the other loop extending therethrough, means whereby the free end of one of the loops may be sprung beneath the free end of the other loop when the loops are brought into operative position, to maintain the same in such position, and means whereby said eyes will be caused to frictionally engage the side members of the other loop when the loops are in operative position.
15. 2. A barrette of the character described, comprising a pair of elongated loop members each being of greater width at one end than

at the other, one of said members having a bar formed across its wide end, a pair of hinge eyes formed at the wide end of the other member, each of said eyes being set at an angle with respect to the length of the member of which it is formed, the cross bar of the first mentioned member being extended through said eyes and the sides thereof being designed, when the members are brought into superposed relation, to frictionally engage under the eyes to hold the members in operative position, and means for catching together ends of the members when in said superposed relation.

In testimony whereof I hereunto affix my signature.

HELEN S. ROWLAND.
